UNITED STATES PATENT OFFICE.

GEORGE W. PARKER, OF NEW YORK, N. Y., ASSIGNEE TO THE PARKER-RUSSELL
MINING & MANUFACTURING COMPANY, OF ST. LOUIS, MISSOURI, A CORPORA-
TION OF MISSOURI.

PROCESS OF REGULATING COMBUSTION.

1,104,000.

Specification of Letters Patent.

Patented July 21, 1914.

Original application filed March 10, 1909, Serial No. 482,551. Divided and this application filed December 9, 1909. Serial No. 532,168.

To all whom it may concern:

Be it known that I, GEORGE W. PARKER, a citizen of the United States, residing at New York city, in the county of New York and State of New York, have invented certain new and useful Improvements in Processes of Regulating Combustion, of which the following is a specification, reference being had to the accompanying drawings.

10 My invention relates to improvements in processes of regulating the combustion of fuel in a furnace and particularly to the regulation of the combustion of fuel in gas producers; and an object of my invention is to 15 provide a process of the character described which will be simple and exceedingly efficient in the accomplishment of the purpose for which it is intended.

Heretofore it has been common to introduce wet steam under the grate-bars of gas producer furnaces; but the use of wet steam results in the saturation of the fuel on the grate-bars, particularly at the front part thereof; and this saturated fuel falls into the 25 ash pit and is wasted.

In carrying out my process, I provide means for introducing superheated steam or steam gas in conjunction with carbon dioxide. Free oxygen may also be introduced with 30 the two gases just named, practically in the form of air. The carbon dioxide will in practice be obtained in the form of waste gases from the recuperator flues of the gas-producer furnace. The amount of air, waste-gas and superheated steam or steam gas will 35 be regulated and measured; and the supply of any one or more of these gases may be entirely cut off at will. By introducing superheated steam the saturation of the fuel upon or near the grate-bars is avoided; for, 40 the steam is so highly superheated that it will remain in the form of steam-gas, even after it comes in contact with the relatively cold surface presented by the grate-bars and the bottom of the fuel bed resting thereon. Hence, by the use of superheated steam, the 45 fire will be kept alive down to even the grate-bars.

In carrying out my new process, the current of superheated steam is introduced below the grate bars and flows up through the fuel-bed, by the heat of which it is dissociated or resolved into its component gases,

hydrogen and oxygen, whereby heat is drawn from the bed of fuel, the temperature of which is thereby kept under control. The current of steam gas may be used to inject a quantity of carbon dioxide gas in the form of waste gases. The waste gases may, if desired, be mixed with free oxygen in the form of air. The carbon dioxide gas in passing through the bed of fuel will be reduced to carbon monoxide; and this endothermic reaction will result in reducing the temperature of the bed of fuel, just as the same result is obtained by the endothermic reaction which results in the dissociation of the steam gas.

In the drawings illustrating the principle of my invention and the best mode now known to me of applying that principle, Figure 1 is a longitudinal vertical section of so much of a gas-producer furnace as is necessary to illustrate an apparatus for carrying out my invention; Fig. 2 is a transverse vertical section of the gas producer furnace shown in Fig. 1; and Figs. 3 and 4 are views similar to Figs. 1 and 2, respectively, but illustrating a modified form of apparatus for carrying out my invention.

The fuel-bed *a* is supported upon the grate-bars *b* and coal is introduced through the throat *c*. Into one of the waste-gas flues *d* extends the inner open end of a gas-pipe *e*, the lower end of which is joined by the *T*-connection *f* with the mixing-pipe *g* and through which flows a part of the waste gases. Another part of the waste gases flows through the waste-gas flue *o* in a manner well known to all skilled in this art. Thus, there are formed two streams of waste gases, one flowing through the pipe *e* and the other through the flue *o*. The air-pipe *h* curves downwardly at its upper end *i* and at its lower end is joined by the *T*-connection *f* to the mixing-pipe *g*. In each of the pipes *e*, *g*, *h*, there is mounted a valve *j* which serves to control the flow of the particular gas which passes through the pipe in which it is mounted. In each of the pipes *e*, *h*, there is fitted a meter *k* which controls and regulates the amount of air or other gas which may pass through the pipe; and the meter *k* may be of the form shown and described in the patent granted Charles E. Sargent, No. 729,511, May 26, 1903. The mixing-pipe

g connects at its lower end with the outer end *m* of the heating coil *n*, which lies in one of the waste gas flues *o* near the bottom of the furnace. Thus, the mixture flowing 5 through the coil *n* is made to traverse a helical path and, while it is passing through the coil, it absorbs heat or heat is transferred to it from the stream of waste gases flowing through the flue *o*. The path of the stream 10 flowing through the coil *n* being winding, this stream is subjected to the action of the heat of the other stream or that through the flue *o* a longer time than if the pipe *n* were straight. Moreover, the coil *n* lies within 15 the stream passing through the flue *o*, an arrangement which is favorable to the absorption of heat by the stream passing through it. The inner end of the heating coil *n* is in the form of a nozzle *p*, having 20 perforations *q* for the egress of the gas. A steam-pipe *r* is fitted with a valve *j* and a meter *k* and is provided with a nozzle *s* which extends into the outer end *m* of the heating coil *n*. Through the pipe *r* flows 25 superheated steam or steam gas which serves as an injector to carry the mixture of waste gas and air from the mixing pipe *g* through the heating coil *n* and the nozzle *p*. By passing the air, waste gases and steam gas 30 through the winding path or coil, a thorough mixing of these gases, as well as a more effectual heating thereof, is obtained.

In Figs. 3 and 4, the mixing pipe *g* is connected with the outer end *m'* of the heating coil *n'*; but the nozzle *s'* of the steam pipe *r'* extends into and connects with the inner end of the heating coil *n'*. The nozzle *p'* of the latter is mounted free to swing upon the hinge-joint *t*, whereby the end of the 40 nozzle *p'* may be dipped into the water *u* in the ash-pit *v*, if it be desired at any time to condense the steam and to cool the gases passing through the nozzle *p'* before their entrance into the furnace through the grate. 45 The depth of the fuel-bed *a* is so great as to insure that the endothermic reaction referred to above shall take place; that is, it is what is commonly known as a deep fuel-bed. By means of the meters *k*, the flow of the

steam gas, waste gas and air may be separately regulated and controlled so as to regulate the combustion of the fuel. 50

This application is filed as a divisional application under my pending application Serial No. 482,551, filed March 10th, 1909. 55

I claim:

1. A process for regulating the combustion of fuel consisting in collecting products of combustion arising from a deep bed of fuel; dividing said products into a plurality of streams; mixing air and steam with one of said streams; leading the mixture thus formed in a winding path through the other of said streams and thereby heating the mixture; and discharging the heated mixture into said deep bed of fuel. 60

2. A process for regulating the combustion of fuel consisting in collecting products of combustion arising from a deep bed of fuel; dividing said products into a plurality of streams; mixing air and steam with one of said streams; controlling the proportions in which the constituents of said mixture enter therein; leading the mixture thus formed in a winding path through the other of said streams and thereby heating the mixture; and discharging the heated mixture into said deep bed of fuel. 70

3. A process for regulating the combustion of fuel consisting in collecting products of combustion arising from a deep bed of fuel; dividing said products into a plurality of streams; mixing air with one of said streams; transferring to the mixture thus formed heat from the other of said streams by passing one of said streams over the other and thereby heating the mixture; introducing steam into said mixture; and discharging the latter into said deep bed of fuel. 80

In testimony whereof I have hereunto set my hand at said New York city this eighth day of December, A. D., 1909, in the presence of the two undersigned witnesses.

G. W. PARKER.
